PUMP CONSTRUCTION

Forrest J. Graef, Fort Wayne, Ind., assignor to
 Tokheim Oil Tank and Pump Company, Fort
 Wayne, Ind., a corporation of Indiana

Application May 8, 1939, Serial No. 272,428

6 Claims. (Cl. 103—126)

This invention relates to pump constructions, and particularly to rotary pumps of the intermeshing gear type and to the method of producing the rotary gear members therein.

It is an object of the invention to produce an intermeshing gear rotary pump of improved construction and operating characteristics, including improved efficiency, smoothness, and quietness of operation.

More specifically it is an object of the invention to produce a rotary gear pump having an improved manner of cooperation between the intermeshing gears wherein the teeth of the gears are brought into engagement as soon as possible and held in engagement as long as possible at the engaging position, thereby producing smooth and quiet operation of the gears and precluding play or backlash between them.

Another object of the invention is to produce a pair of cooperating gear members having the foregoing features of construction and operation, particularly for use in a rotary gear pump.

A further object of the invention is to incorporate the foregoing features in a pump of the internal gear type including a toothed rotor gear, an idler gear disposed internally of the rotor teeth and in geared engagement therewith, and an intermediately disposed crescent member; and wherein the rotor teeth are substantially semi-cylindrical in form.

Still other objects, advantages and features of the invention will appear from the following specification when taken in connection with the accompanying drawings wherein a preferred embodiment of the invention is illustrated.

In the drawings wherein like reference numerals refer to like parts throughout:

Fig. 1 is a sectional view of a pump structure of the aforesaid internal gear type constructed in accordance with the principles of the invention;

Figs. 2 to 9 inclusive are partial detail views, on an enlarged scale, illustrating the successive steps in the engagement of an idler gear tooth with the cooperating rotor teeth; and

Fig. 10 is an illustrative view on a further enlarged scale showing the method of developing the curve for the outer portion of the idler gear tooth.

Referring more particularly to the drawings, and first to Fig. 1, the pump construction illustrated comprises a rotor member 10 adapted to be driven from a shaft 11 and provided with a series of teeth 12 annularly disposed and projecting parallel to the axis of the shaft 11, in a manner well understood in pump constructions of

this type. The shaft 11 by which the rotor is adapted to be driven projects through the rear side of the pump casing and is adapted to be connected to any suitable power source. An idler gear 13 is mounted on a shaft 14 journaled in the front of the pump casing, and carries teeth 15 which cooperate with the rotor teeth 12. As will be seen the axes of shafts 11 and 14 are offset or eccentrically disposed. A crescent member 16 carried by the front of the pump casing is interposed between the rotor and idler gear, and engages the teeth thereof at a position opposite to the point of intermeshing tooth engagement indicated by the reference numeral 17. The ends 18 of the idler gear teeth are curved accurately to conform to the interior curved surface of the crescent member for sealing engagement therewith, and also conform in a general way to the curvature of the boss 19 formed on the pump casing. Similarly the rotor teeth 12 are provided with internally facing indentations or curved surfaces 20 accurately conforming to the curvature of the exterior side of the crescent member and adapted to be brought into sealing engagement with the crescent during the operation of the pump as shown in Fig. 1. The outwardly facing surfaces 21 of the rotor teeth are curved accurately to conform to the curvature of the casing boss 19 and to the curvature of the lower casing portion 22, for sealing engagement with these casing parts. The rotor teeth are generally semi-cylindrical in cross section as will more specifically appear hereinafter.

In operation, as the pump rotor is driven in a clockwise direction from its driving shaft 11, fluid which may be liquid, such for example as gasoline, will be pumped from the inlet 23 to the outlet 24 in the manner illustrated by the arrows in Fig. 1, the liquid being carried in the pockets between the teeth of the rotor and idler gear. Liquid is prevented from leaking back from the outlet to the inlet side of the pump by reason of the intermeshing engaging of the gears as indicated at 17, and by the crescent member 16 which engages the rotor and idler gear teeth sealing the pockets therebetween. The idler gear receives its rotary motion by reason of its geared engagement with the rotor.

While the invention has been illustrated as applied to an internal gear pump of the foregoing type, a pump to which it has particular applicability, it is to be understood that certain features of the invention may be adapted for use with other types of structures having inter-

meshing gears, including other types of rotary gear pumps.

Referring to Figs. 2 to 9 inclusive illustrating the various positions which the idler gear teeth assume in their cooperation with the rotor teeth, it will be seen that in Fig. 2 the idler gear tooth 15, while approaching the position of intermeshing engagement, has not as yet contacted either the leading rotor tooth 12a or the trailing rotor tooth 12b. As rotation takes place in a clockwise direction, as indicated by the arrow in Fig. 2, the idler gear tooth first engages the trailing tooth 12b of the rotor, as shown in Fig. 3. As rotation continues, the idler gear tooth next engages the leading tooth 12a of the rotor, maintaining its contact with the trailing rotor tooth 12b, as shown in Fig. 4. In Fig. 5 the idler tooth has reached its fully meshed position, corresponding to the position 17 shown in Fig. 1, in which position it remains in engagement with both of the rotor teeth. In Fig. 6 the idler tooth has passed the position of full mesh, but it still maintains its contact both with the leading rotor tooth 12a and the trailing rotor tooth 12b. In Fig. 7 the idler tooth has left its contact with the trailing tooth 12b, but still maintains its contact with the leading rotor tooth 12a. In Fig. 8 the contact between the end of the idler gear tooth and the leading rotor tooth 12a is still maintained, and in Fig. 9 the position of the parts is illustrated after the idler tooth has passed the position of mesh sufficiently to be removed from all contact with the teeth of the rotor. As will be seen, the idler gear tooth is maintained in contact with the teeth of the rotor from a position well in advance of the mesh station 17 to a position well on the other side thereof, insuring smooth and quiet operation, promoting pump efficiency, and preventing play or backlash between the gears. This maintained engagement is provided by the particular shaping of the idler gear teeth, and particularly the outer side portions thereof which shaping and its method of production constitute a principal feature of the invention as will now be described with reference to Fig. 10.

Assuming that it is desired to construct a pump wherein the rotor will have 9 teeth and the idler gear 7 teeth, as shown for example in Fig. 1, it is well known in the art of gearing that every gear has a so-called pitch circle, and in the case of two intermeshing gears the pitch circles are tangent at the point of mesh; and knowing the gear or speed ratio which the gears are to have, the ratio of the radii of the pitch circles or the size of the gears can be determined. In Fig. 10 a rotor tooth 12 and an idler gear tooth 15 are shown in contact, on a further enlarged scale, the rotor tooth being disposed at the full position of mesh 17 (Fig. 1) as distinguished from the position of the gears shown in Fig. 1 wherein the idler gear tooth is shown in the full position of mesh. The axis of the idler is indicated at O, and the axis of the rotor at Q in Fig. 10, the eccentricity of the gears corresponding to the eccentricity of the shafts 11 and 14, therefore being represented by the distance OQ. The pitch circle for the idler gear is represented by the line F and the pitch circle for the rotor by the line H, the two pitch circles being in tangency and in contact at the point E, the position of mesh. As is known, in the case of intermeshing gears the gear or speed ratio is inversely proportional to the radii of the gear pitch circles. In the particular selected em-

bodiment, the rotor and idler having 9 and 7 teeth respectively, the speed ratio of the rotor and idler will be 7 to 9, and accordingly the ratio of the pitch circles radii will be 9 to 7. In other words the radii of the pitch circles of the rotor and idler, represented by the lines X and Y respectively in Fig. 10 bear the ratio of 9 to 7, and for any given eccentricity OQ, the values of the radii and resultingly the size of the gears may be determined, or for any given relative gear sizes the required eccentricity may be calculated.

As previously stated, the rotor teeth are semi-cylindrical in contour, the radius of the tooth cylinder being represented by the line R in Fig. 10; and in order to insure an acute angle for the corner 25 of the tooth preventing the formation of reverse curvature, the center C from which the radius R is swung is located somewhat beyond or externally of the exterior surface 21 of the tooth. Preferably the trough portions 26 of the idler gear teeth are also semi-cylindrical in shape, being illustrated as formed with the radius J in Fig. 10. To provide a clearance space 27 between the rotor tooth and the trough of the idler teeth, the center D from which the radius J is swung is located somewhat inwardly of the center C, and to provide contact between the rotor tooth and the idler tooth at a point such as indicated at A the radius J is made slightly smaller than the radius R. The width of the rotor teeth with respect to the width of the idler teeth will be determined by the size of the radius R, and these values are selected so that the size of the teeth will be substantially as shown in Fig. 1, the rotor teeth which have considerable unsupported axial length being appreciably wider than the idler teeth to impart strength thereto.

The idler gear tooth is reversely curved from the point A to the point B where the side wall of the tooth and the outer surface 18 thereof join. It is this surface AB which insures the maintained contact between the idler and rotor teeth, in the manner previously described, and its method of formation constitutes a principal feature of the invention.

To form the surface AB the rotor may be considered as rolling around the idler while it is held stationary, the pitch circles of the gears rolling in contact as they do in actual operation; and the rotor tooth may be considered in the nature of a grinding or cutting wheel as indicated by the broken line U, the rotor tooth thus grinding or cutting the surface AB on the idler tooth to the precise shape that it should have to just maintain contact with the rotor tooth during the actual operation of the gears.

Assume any point such as K on the pitch circle H of the rotor. Locate another point K₁ on the pitch circle F of the idler so that the length of the line EK₁ is equal to the length of the line EK. As the rotor is rolled around the stationary idler gear by means of the pitch circles, the point K will move down and coincide with the point K₁ when the rolling operation has progressed to the K-K₁ position to bring the pitch circles into tangency at this point. As will be seen by reference to Fig. 10 the point of tangency E and the centers O and Q are in a straight line when the gears are in the original position illustrated. Similarly when the point of tangency has progressed to the point K₁, this new point of tangency, the idler center O, and the new center Q₁ for the rotor will be in a straight line. Accordingly to find a new center Q₁ for the rotor a

straight line may be drawn through the points K_1 and O to the intersection of the arc M drawn about the center O with the radius OQ .

To find the position which the rotor tooth 12 will occupy with respect to the idler gear tooth 15 when the point of tangency between the gears has progressed to the position K_1 arcs may be swung to determine the point C_1 in such manner that the line C_1K_1 is equal in length to the line CK , and the line C_1Q_1 is equal to the line CQ . The two triangles CKQ and $C_1K_1Q_1$ are equal, and they represent different positions assumed by the same parts of the rotor as it is rolled on the pitch circle of the idler gear to move the point of tangency between the gear pitch circles from the point E to the point K_1 . The point C_1 accordingly indicates the position which the center of the rotor tooth 12 will assume with respect to the idler tooth 15 when the point of mesh has progressed to the point K_1 , and if the radius R_1 equal to the radius R is swung from the center C_1 an arc T_1 is found which determines the point of contact between the rotor and idler teeth when the point of tangency has progressed to the point K_1 , and finds the curvature which the surfaces AB must have at such point to maintain contact with the rotor tooth.

To determine additional points for the surface AB , additional points such as P and P_1 are laid out on the pitch circles H and F so that the length of the line EP equals the line EP_1 . When the rolling of the rotor about the idler pitch circle has progressed to bring the point P into position to coincide with the point P_1 , new positions Q_2 for the rotor center and C_2 for the center of the rotor tooth may be found in the manner previously described. The same process may be followed to find the additional rotor tooth centers C_3C_4 etc., and by swinging the radii R_2R_3 and R_4 from these centers arcs $T_2T_3T_4$ are found which determine the sequential points of contact between the rotor and idler teeth and accordingly determine the proper curvature for the surface AB . Obviously the process may be repeated sufficiently to accurately determine the entire length of the surface AB , but on the drawings in the interest of simplification only a few illustrative examples have been shown. Considering the rotor tooth as a grinding or cutting wheel, as it moves successively to the centers C_1, C_2, C_3 , and C_4 the surfaces AB will be accurately shaped.

In accordance with the foregoing method the surface AB on the outer end of the idler gear tooth is in effect cut or shaped by the rotor tooth itself, the rotor tooth being moved with respect to the idler tooth in the actual manner in which motion takes place when the gears are in operation. The surfaces AB which will be similarly formed on the two sides of each of the idler teeth, are accordingly accurately shaped so that they continuously maintain contact between the rotor and idler gear teeth from the point of initial engagement, such for example as illustrated in Figure 3 to the point of final engagement such as is shown in Fig. 8. Improved efficiency,

smoothness and quietness of operation is obtained.

It is obvious that various changes may be made in the specific embodiment of the invention heretofore described and in the several method steps set forth without departing from the spirit of the invention. Accordingly the invention is not to be limited beyond the limitations set forth in the following claims.

10 The invention is hereby claimed as follows:

1. A rotary pump of the internal gear type comprising a rotor, and a mating gear engageable therewith, the rotor teeth being provided with convex cylindrical surfaces and the mating gear being provided with concave cylindrical tooth surfaces cooperable with the cylindrical tooth surfaces of the rotor, the center of curvature of the cylindrical tooth surfaces of the mating gear being radially inwardly displaced from the center of curvature of the cylindrical tooth surfaces of the rotor at the point of meshing engagement.

2. A rotary pump of the internal gear type comprising a rotor, and a mating gear engageable therewith, the rotor teeth being provided with convex cylindrical surfaces and the mating gear being provided with concave cylindrical tooth surfaces cooperable with the cylindrical tooth surfaces of the rotor, the radius of curvature of the mating gear cylindrical tooth surfaces being less than the radius of curvature of the cylindrical rotor tooth surfaces, and the center of curvature of the cylindrical tooth surfaces of the mating gear being radially inwardly displaced from the center of curvature of the cylindrical tooth surfaces of the rotor at the point of meshing engagement.

3. A rotary pump of the internal gear type comprising a rotor having circumferentially disposed continuous teeth, and a mating gear engageable therewith, the rotor teeth being provided with convex cylindrical surfaces and the mating gear being provided with concave tooth surfaces cooperable therewith, the center of curvature of said convex cylindrical rotor tooth surfaces being disposed radially outwardly from the outer edges of the rotor teeth.

4. A rotary pump as defined in claim 3 wherein said concave mating gear tooth surfaces are cylindrically shaped.

5. A rotary pump as defined in claim 3 wherein said concave mating gear tooth surfaces are cylindrically shaped, and wherein the radius of curvature of the mating gear cylindrical tooth surfaces is less than the radius of curvature of the cylindrical rotor tooth surfaces.

6. A rotary pump as defined in claim 3 wherein said concave mating gear tooth surfaces are cylindrically shaped, and wherein the center of curvature of the cylindrical tooth surfaces of the mating gear is radially inwardly displaced from the center of curvature of the cylindrical tooth surfaces of the rotor at the point of meshing engagement.
